CONTROL MEANS FOR RECTIFIER TUBES

Donald V. Edwards, Montclair, N. J., assignor to
 Electrons, Inc. of Delaware, a corporation of
 Delaware

Application December 10, 1932, Serial No. 646,625

11 Claims. (Cl. 175—363)

This invention relates to the control of gaseous discharge rectifier tubes having control grids, i. e., tubes wherein the starting of an arc discharge is controlled by a grid element and extinguished by reducing the plate potential to zero.

The object of the invention is to provide means for controlling the tube, which means shall require minimum energy without sacrifice of dependability.

10 A further object is to provide an improved grid transformer for such tubes.

The invention will be described with reference to the drawing in which

15 Fig. 1 shows schematically a typical circuit arrangement employing the invention, and

Fig. 2 is a diagram showing the relation of various voltages in the circuit shown in Fig. 1.

Referring to Fig. 1, an alternating current source 1 energizes transformer 2, the secondary 20 coil 3 of which is connected to the plates 4, 4 of the grid control rectifiers 5, 6 in a full-wave circuit which includes a load shown schematically at 7, and connected between the midpoint of the transformer secondary and the midpoint of the 25 secondary 8 which feeds the cathode circuit 9. At 10 is a source of control energy having internal resistance which, for the purpose of describing this invention, may be considered as a resistor connected across the source of potential 1. The 30 invention applies equally well if instead of resistance 10 the source of control energy is the variable current in the plate circuit of a vacuum tube, or any of the commonly used bridge circuits, since, in both cases, the control circuit may be considered as having internal resistance equivalent to 35 resistance b, c. The controlling potential across leads 11 and 12, at least the former of which preferably is variable, operates the primaries of transformers 13 and 14. The secondary of transformer 13 is connected between the center tap of the filament winding and grid of tube 5 with a series resistance 15 which may be an external resistance, or, preferably, the internal resistance of the secondary winding of transformer 13. 40 Transformer 14 is connected to tube 6 in a similar manner through resistance 16. If the sliding contact 11 is at b, no voltage is generated and the grids assume the potential of the center tap of the filament, allowing both tubes to start each 45 cycle and during the discharge pass current through load 7. If contact 11 is moved slightly toward c, an A. C. voltage is impressed on the primaries of transformers 13 and 14, generating a voltage in 13 such that the grid of tube 5 will 50 be negative when the plate is positive, and, like- wise, a voltage in 14 such that the grid of tube 6 will be negative when its plate is positive. This will prevent the arc from starting in both tubes and no current will flow through either tube. If the tubes are of the type requiring positive bias 5 to start, the operation will be the same except that no current will flow until contact 11 is moved to point g. The voltage generated will then make the grids more positive than the trigger point on the respective half cycles when the plates are 10 positive and current will flow through the load.

A characteristic of the grid controlled gaseous discharge tube is that while the discharge is present the grid if near cathode potential will draw energy from the plate circuit and feed it back 15 into the grid circuit. Ordinarily the energy so fed back builds up magnetic flux in the core of the transformer. When the discharge in the tube stops at the end of the active cycle, this flux representing stored energy tends to generate a voltage 20 in the transformer primary causing current to flow back into the control source; and in the secondary, tending to influence the grid potential. This is shown in Fig. 2 where curve k is the potential from the grid to the center tap in 25 a well designed circuit employing a transformer of low energy storing capacity. If the circuit employs the usual design of transformer, the curve will not follow the solid portion of curve k which lies to the right of the negative peak but 30 instead will follow some curve similar to the dotted portion shown at n. Curve d is the plate voltage of tube 5, and m the grid potential when no feed-back is present, as when the grid just prevents starting. It can be seen that once the 35 tube passes current, control on the succeeding cycles will be affected. On the second half cycle shown, the grid is more negative due to stored energy by the amount p. This will not affect tube 5 because its plate is negative but an approximately equal voltage in the opposite direction will be induced into the grid of 6 making it positive and allowing it to start if the amount p is sufficiently large, for instance, if the curve followed the dotted portion n. In a half-wave circuit containing only tube 5, control on the next positive cycle would be influenced to the extent shown at s, tending to prevent discharge but ineffective unless a curve similar to u is followed. Thus when the usual audio-frequency transformers are used for transformers 13 and 14 several hundred times as much energy input will be required to control the tubes than would be necessary if direct current were applied directly to the grids. Moreover, there is a strong tendency 55

for the tube that should be out to pass current during an occasional cycle, or to make the cut-off point indefinite, there being quite a large range where the tube, instead of going out sharply, will 5 flicker periodically.

I have found that these difficulties can be overcome by the use of special grid transformers making it possible to get sharp control with much less power input. To do this the transformer is 10 designed to store as little energy as possible. This insures that the available control energy is used mainly for supplying transformer losses and generating voltage on the grid of the tube rather than in overcoming fed-back energy. 15 Specifically, I make the transformer according to the following method:

The secondary 17, 18 is wound to give the desired voltage on the grid; present-day tubes require about 4 volts to allow for variation between 20 tubes plus variation of tubes with life. The smallest possible wire is used, preferably small enough to give an internal resistance equal to the highest grid resistance compatible with good tube operation. If, for instance, the grid current limit of control tubes available is 10 micro-ampères or under, a resistance of 10,000 ohms will be satisfactory, since the variation between tubes due to varying grid currents will not amount to more than $\frac{1}{10}$ volt. 25

It is necessary to know from the tube data approximately how much current will return through the grid circuit after the discharge has started with this value of resistance. A typical value for present-day tubes is 300 micro-ampères peak. The iron circuit of the transformer is 30 designed so that the energy stored in it as magnetic flux by this amount of current flowing in the secondary can be substantially dissipated by the primary windings in less time than the interval during which both tubes are out at the end 35 of each active cycle. The mathematical integration involved in determining this time is too complicated to offer much practical help. The simplest solution at present seems to be to take 40 small increments of time and calculate point by point the grid voltage during and after an operating cycle. A sufficiently accurate solution may be found in the following manner: From the tube characteristic it is fairly simple to calculate 45 the current flowing in the transformer at the end of an active cycle. After the discharge ceases a current will flow for an instant giving the same number of ampere turns on the core of the transformer. Then over a small increment of time, 50 say 5°, the voltage necessary to make this primary current flow in the transformer primary circuit is determined from the circuit constants and internal resistance of the control source. The decrease in flux in the core necessary to generate 55 this voltage is easily calculated and thus the flux at the end of the small increment of time determined. From the magnetization curve of the transformer, the current flow corresponding to this flux is determined. Using this value as the 60 initial current for another small increment of time the same method is followed for it and so on until a complete cycle is obtained. Then plotting the potential of the grid after an active cycle 65 will show the effect of the stored energy on the control for the next active cycle. If such a curve is made for a number of values of internal resistance of the control source, it is found that decreasing resistance prolongs the time necessary for dissipating energy. 70

The energy stored in the core will be reduced 75

if an iron which has a sharp magnetic saturation point is used and is operated to give the designed secondary voltage at just under saturation. It also requires that the finest possible wire be used for the secondary, and the winding factors of both primary and secondary be made as high as possible to reduce the weight of iron used. This will result in a transformer of low efficiency and high magnetizing current. However, in spite of this the energy required to control the tubes 10 is greatly reduced and the sensitivity increased because the control source does not have to overcome the energy fed back from the control tubes during the operating part of the cycle. 15

Less power is required if two transformers are used with two separate cores; one for each tube rather than both secondaries on one core although the total losses are higher.

Most applications of control tubes are for 60-cycle circuits, in which case it is possible to use 20 transformers having high core losses. This will result in the transformer having a low cut-off frequency but the stability of the circuit will be greatly improved because transients picked by leads 11 and 12 will not build up voltage across 25 the transformer and allow false operation of the tube. It is then only necessary to shield the leads from the transformer to the grid and also the grids themselves by any suitable means, as for example the metallic casing 19, to prevent pick- 30 up stray fields. Some of the grid current before discharge of the grid control rectifier tubes is highly irregular in wave form. If the core losses are relatively high, the impedance of the transformer to these waves is reduced and tube 35 stability increased.

In view of these considerations it would seem that the real limit to the voltage step-up ratio of transformers for controlling grid rectifiers is fixed by the current available to supply core loss 40 and magnetizing current. This sets a premium on building the transformer just as small as possible, which is in direct contradiction to present conceptions of good transformer design. Transformers with as high as 1/200 voltage step-up 45 ratio have been operated satisfactorily, and there seems to be no reason at present why this value cannot be increased to 1/1000 or more.

In some cases the magnetizing current of the transformers 13 and 14 will shift the phase of 50 their secondary voltages. This can be compensated for, if necessary, by shifting the phase of the input energy to the control source 10 by any of the well-known means. In other cases, advantage can be taken of this phase shift to allow 55 triggering the tubes before the crest of the plate voltage.

The invention has been described with respect to the all-on, all-off operation of a full wave circuit. The principles apply to half wave circuits in the same manner except that the time available for the collapse of flux in the core may be greater. The principles also apply where a phase shift control circuit is used to obtain graduated control rather than the all-on, all-off circuits shown. 60

What I claim is:—

1. The combination with a grid controlled gaseous rectifier, of a grid transformer supplying control voltage to the grid of the rectifier, and 70 means for dissipating the voltage induced in said transformer by the cessation of the gaseous discharge.

2. The combination with a grid controlled gaseous rectifier of means including a reactive 75

- element for applying an alternating control voltage to the grid, and means for reducing the current induced in said control means by the action of the gaseous discharge.
5. The combination with a grid controlled gaseous rectifier of a grid transformer supplying alternating control voltage to the grid of the rectifier, and means for reducing the storage of energy in the transformer due to the cessation of the discharge.
10. The combination with a grid controlled gaseous rectifier of a transformer supplying alternating control voltage to the grid of the rectifier, the core of said transformer being adapted to be nearly saturated in providing the grid current at the control voltage normally required to start the gaseous discharge.
15. A grid transformer for use with grid controlled rectifier tubes wherein the magnetic core is so small that the energy stored from an operating cycle will be substantially dissipated before the start of the next operating cycle.
20. A transformer for use with grid controlled gaseous rectifier tubes having a secondary wound with wire of approximately the size to carry the designed grid current before starting, and having the core designed to be worked at a flux density slightly under the saturation point in providing the normal grid control potential.
25. 7. The method of operating a grid controlled gaseous rectifier with an alternating current source of control voltage, said rectifier having reactance in its control grid circuit, which consists in making the said reactance a minimum consistent with its providing the necessary grid voltage to start the gaseous discharge, and dissipating before the succeeding control period a substantial part of the grid voltage induced by the cessation of the discharge.
30. 8. The combination with a grid controlled gaseous rectifier of a transformer having its primary connected to a source of control energy for supplying alternating voltage to the grid of the rectifier and having its secondary connected in the grid circuit of the rectifier, said grid circuit being conductively insulated from said source, and the core and secondary of said transformer being adapted to give a high ratio of resistance to reactance.
35. 9. The method of operating a grid controlled gaseous rectifier with an alternating current source of control voltage, said rectifier having inductive impedance in its control grid circuit, which consists in making the reactive component of said impedance a minimum and its resistance a maximum consistent with its providing the necessary grid voltage to start the gaseous discharge, and dissipating before the succeeding control period a substantial part of the grid voltage induced by the cessation of the discharge.
40. 10. A grid transformer in combination with grid controlled rectifier tubes wherein the magnetic core of said transformer is so small that the energy stored from an operating cycle will be substantially dissipated before the start of the next operating cycle, the secondary circuit of said transformer having a high ratio of resistance to reactance.
11. A transformer of small core dimensions for grid controlled rectifier tubes, together with resistance in series with the grid of a value relative to the core of said transformer to permit developing the desired starting control voltage on the grid but limiting the grid current drawn from the operating discharge to prevent storage of more energy in the said core than can be substantially dissipated between operating cycles.
